(57) **CLAIM**

The ornamental design for a television receiver as shown and described.

DESCRIPTION

1.1 : Perspective

1.2 : Front

1.3 : Back

1.4 : Left

1.5 : Right

1.6 : Top

1.7 : Bottom

The characteristic features of the design lie in the shape; the claimed design is a television receiver in which the display unit and the case are integrated into one body, and is easy to carry and move; reproduction **1.8** shows a state that the claimed design is closed; reproduction **1.9** shows a state of the handle being pulled out and wheels are installed; reproductions **1.8** and **1.9** form no part of the claimed design; the broken lines indicate portions of the article that form no part of the claimed design; the broken lines in the reproduction **1.9**, showing wheels, illustrate environmental structure and form no part of the claimed design.

The broken lines indicate portions of the television receiver that form no part of the claimed design.

1 Claim, 7 Drawing Sheets
